(57) **CLAIM**

The ornamental design for a lanyard maker, as shown and described.

DESCRIPTION

FIG. 1 is a perspective view of a lanyard maker showing my new design;

FIG. 2 is a top plan thereof;

FIG. 3 is a front view thereof;

FIG. 4 is a right side view thereof;

FIG. 5 is a rear view thereof; and,

FIG. 6 is a left view thereof.

The broken lines shown in the drawing disclosure are for illustrative purposes only and form no part of the claimed design.
